HAMMER-MILL MIXER COMBINATION

Harry H. Harris, Palo Alto, Calif., assignor to
Enterprise Engine & Foundry Company, San
Francisco, Calif., a corporation of California

Application December 31, 1940, Serial No. 372,619

5 Claims. (Cl. 83—11)

This invention relates to vertical hammer mills or disintegrators and the invention has for its object improvements whereby the mixing of various modifying agents with the disintegrated material is facilitated.

Other advantages of the improved construction will appear in the following description and accompanying drawing.

In the drawing:

Fig. 1 is a vertical section of the mill showing all of its main parts and the relation of my improvement thereto.

Fig. 2 is a fragmentary cross section of Fig. 1 taken along the line 2—2 of Fig. 1.

Briefly described, my improvement in a vertical hammer mill comprises extending the rotor shaft downward below the lowest bearing through a special receiving chamber for the disintegrated product of the mill, and providing extra mixing blades on the shaft within the receiving chamber, and means for introducing extraneous materials to the chamber for mixing with the disintegrated and screened product from the mill rotor, so as to produce any desired blended product before finally discharging the material. As a further feature an exhaust fan or pump may be connected to the lower end of the rotor shaft to forcibly discharge the blended or mixed product.

In the drawing the vertical hammer mill comprises the old and well known features of a frame 1 having an outwardly projecting circular supporting flange 2 with bolt holes 3 for securing it to a foundation, while at the upper end the frame is of reduced diameter as at 1', secured to the upper end of which is a spacing frame 4, in turn supporting a motor 5, the shaft 6 of which is coupled at 7 to the rotor shaft 8 of the mill. The rotor shaft extends downwardly through a cylindrical chamber formed by curved screen sections 9, and the shaft is rotatably positioned in bearings 10 and 11, the latter of which preferably supports the weight of the shaft, and is supported by ribs or spider arms 12 extending radially from a circular flange 13 in turn supported within a circular flange 14 connected to frame 1 by radially extending ribs or spider arms 15.

The mill frame 1 includes vertical members 16 spaced outwardly from the screen shell 9 and around which members is a sheet metal enclosing casing 17 made in two or more sections and clamped in place around the mill as by pivot bolts 18 and wing nuts 19 as best shown in Fig.

2, or otherwise removably secured or hinged thereto. Within the screen chamber the shaft 8 is provided with the usual beater arms or so-called hammers 20 which project radially from the shaft, or rather from a hub or hub sections 21 suitably secured to the shaft, and which beater arms may be of any shape, size, or length, fixed or pivotally mounted, and in any desired arrangement, as commonly used in mills of this type for beating and disintegrating material fed into the upper end of the screen chamber from a feed chute 22, so that by the rapid revolution of the beater arms the material is broken up or disintegrated to an extent depending on the nature of the material, the shape, length and speed of the beaters. The finely divided material is thrown through the openings in the screen shell 9 surrounding the rotor and, together with the remainder of the finely divided material which passes through a horizontally disposed screen 23 which extends across the rotor chamber beneath the lowest beater arm, all falls in direction of the arrows into a conical receiver 24 secured to the bottom of the frame flange 2 as by bolts 25 and to the lower conical end of which receiver a horizontally positioned ejecting fan or centrifugal pump 26 is secured so as to receive all of the material from the receiver 24 for ejection from the pump outlet 27 as indicated by the horizontal arrow to any point desired.

The ejecting pump or fan is of the conventional type and is conveniently driven by the lower end of the rotor shaft 8 which may be additionally supported by a bearing 30 at the lower end of the conical receiver 24 if desired. The conical receiver assures all of the material from the mill converging and falling into the fan. Between the pump and the screens through which the disintegrated material falls are several mixing arms 28 projecting from the shaft for mixing or blending with the disintegrated material any extraneous materials either powdered or liquid, or which require some disintegration, as may be introduced into the receiver 24 through a secondary feed chute 29 entering the base of the mill frame just above the receiver 24, and which extraneous materials may be introduced by means of any desired feed controlling means not shown.

As mixing arms 28 travel at a high rate of speed, their normal tendency to lift the material in receiver 24 to the largest diameter of the receiver is overcome by having them relatively narrow in vertical cross section and slightly slanted (propeller-like) as indicated at 33 so that a

slight tendency to force the materials downwardly will result, so that they will all fall readily into the pump inlet after thorough mixing.

This general type of vertical hammer mill with both cylindrical screen surrounding the rotor as well as flat screen across the lower end of the rotor chamber, also a receiver below and discharge pump, is shown in prior Patent #1,977,771 and likewise the general features in numerous other prior art patents, but the provision for introduction of extraneous materials to the disintegrated material and supplementary mixing blades carried by the rotor shaft all in a supplementary mixing chamber below the disintegrating chamber at a point preceding the discharge pump inlet, I believe to be new, and I therefore claim:

1. In a vertical hammer mill having a rotor mounted on a vertical shaft with laterally extending hammers revolvable within a vertically positioned cylindrical screen, and a mill casing or outer wall surrounding and spaced outwardly from the screen whereby material fed into the upper end of the cylindrical screen will be disintegrated by the revolving hammers and hurled through the screen to fall from the lower end of the space between the screen and the mill casing, the improvement which comprises a hollow receptacle below said screen and said space between the screen and the mill casing and forming a continuation of said casing so as to receive the disintegrated and screened material falling from said space an outlet in the bottom of the receptacle, said vertical shaft of the rotor extended downwardly into said receptacle and terminating adjacent the outlet in the bottom thereof, mixing blades in said receptacle carried by the extended shaft and arranged to thoroughly mix the disintegrated and screened material as it falls from said space, means for introducing extraneous material into the upper portion of said receptacle for simultaneously mixing with said disintegrated and screened material, and a fan on the lower end of the vertical shaft for passing the mixed materials from the outlet in said receptacle.

2. In a vertical hammer mill having a rotor mounted on a vertical shaft with laterally extending hammers revolvable within a vertically positioned cylindrical screen, and a mill casing or outer wall surrounding and spaced outwardly from the screen whereby material fed into the upper end of the cylindrical screen will be disintegrated by the revolving hammers and hurled through the screen to fall from the lower end of the space between the screen and the mill casing, the improvement which comprises a hollow receptacle below said screen and said space between the screen and the mill casing and forming a continuation of said casing so as to receive the disintegrated and screened material falling from said space a cylindrical housing at the lower end of the receptacle, a discharge opening in said housing, said vertical shaft of the rotor extended downwardly into said receptacle and terminating within the cylindrical housing, mixing blades in said receptacle carried by the extended shaft arranged to thoroughly mix the disintegrated and screened material as it passes through the receptacle, means for introducing extraneous material into the upper portion of said receptacle for simultaneously mixing with said disintegrated and screened material, and a fan within the cylindrical housing and attached to the lower end on the vertical shaft for passing the mixed materials through the discharge opening in said

housing, said mixing blades formed with angular lower faces tending to urge the mixed material toward the discharge opening.

3. In a vertical hammer mill having a rotor mounted on a vertical shaft with laterally extending hammers revolvable within a vertically positioned cylindrical screen, and a mill casing or outer wall surrounding and spaced outwardly from the screen whereby material fed into the upper end of the cylindrical screen will be disintegrated by the revolving hammers and hurled through the screen to fall from the lower end of the space between the screen and the mill casing, the improvement which comprises providing a hollow receptacle below said screen and said space between the screen and the mill casing and forming a closed continuation of said casing so as to receive the disintegrated and screened material falling from said space, said vertical shaft of the rotor extended downwardly into said receptacle, mixing blades in said receptacle carried by the extended shaft arranged to thoroughly mix the disintegrated and screened material as it falls from said space, and means for introducing extraneous material into the upper portion of said receptacle for simultaneously mixing with said disintegrated and screened material, and means for passing the mixed materials from a common outlet at the bottom of said receptacle, said mixing blades formed with angular faces tending to urge the mixed material toward said outlet, said receptacle being conical with its smaller end directed downwardly, and said mixing blades being in several rows one below the other and of decreasing length toward the lower end of the receptacle to slow up the rotary motion of the material.

4. In a vertical hammer mill having a rotor mounted on a vertical shaft with laterally extending hammers revolvable within a vertically positioned cylindrical screen, and a mill casing or outer wall surrounding and spaced outwardly from the screen whereby material fed into the upper end of the cylindrical screen will be disintegrated by the revolving hammers and hurled through the screen to fall from the lower end of the space between the screen and the mill casing, the improvement which comprises providing a hollow receptacle below said screen and said space between the screen and the mill casing and forming a closed continuation of said casing so as to receive the disintegrated and screened material falling from said space, said vertical shaft of the rotor extended downwardly into said receptacle, mixing blades in said receptacle carried by the extended shaft arranged to thoroughly mix the disintegrated and screened material as it falls from said space, an inlet conduit at the upper part of said receptacle adapted for feeding extraneous materials into said receptacle for simultaneous mixing with said disintegrated and screened material, said receptacle being conical with its small end directed downwardly and provided with a discharge opening at the lowest point, a centrifugal discharge fan secured across said discharge opening with its suction side arranged to receive the discharged material, said mixing blades formed to urge the material downwardly into said discharge fan.

5. In a vertical hammer mill of the character described, means forming a chamber at the bottom of the mill arranged to receive the disintegrated material, the rotor shaft of the hammer mill being extended downwardly into said chamber, mixing blades secured to said shaft in said

chamber arranged to mix the disintegrated material received from the mill, and means for feeding extraneous materials to said chamber for mixing with said disintegrated material, said chamber being conical with its smaller end directed downwardly and provided with a discharge opening at its lower end, and said mixing blades

formed with angular faces tending to urge the mixed materials toward said opening, and a centrifugal discharge fan secured across said opening to receive the materials urged toward it by 5 said blades.

HARRY H. HARRIS.
